Attorneys.

UNITED STATES PATENT OFFICE.

GEORGE T. SOUTHGATE, OF BROOKLYN, NEW YORK.

SECTIONAL CEMENT TELEGRAPH-POLE.

1,244,652.

Specification of Letters Patent. Patented Oct. 30, 1917.

Application filed June 16, 1915. Serial No. 34,492.

To all whom it may concern:

Be it known that I, GEORGE T. SOUTHGATE, a citizen of the United States, residing at Brooklyn, in the county of Kings and State of New York, have invented certain new and useful Improvements in Sectional Cement Telegraph-Poles; and I do hereby declare the following to be a full, clear, and exact description of the invention, such as will enable others skilled in the art to which it appertains to make and use the same.

My invention relates to cement poles such as are used for the support of electrical conductors in the construction of electric power lines and telegraph and telephone systems and for the support of span wires in electric railway systems.

The objects of my invention are:

To produce a pole substantially parabolical or tapering in longitudinal section and circular in cross section, which shall be composed of a plurality of sections, each section being pre-cast and pre-aged; said sections being of such a length that they can be readily transported and readily assembled in the field;

To form said sections with a metallic reinforcement and a cement covering so as to provide for ample tensile and compressive strength and a high and uniform lateral strength against flexure;

To provide a joint for joining said sections together in such a manner as to insure that the joint will be as strong as the rest of the pole and that the metallic elements of said joint shall be thoroughly protected against the action of the elements;

To provide a sectional reinforced cement pole which shall be practically homogeneous in structure when erected; free from flaws; which shall be better and cheaper than the cast iron, wrought iron or monolithic cement pole because of the less total weight of metal; the greater flexibility; the less brittleness; the greater resistance against corrosive action; which shall be more artistic in appearance than either the cast iron or wrought iron pole; which shall require no painting and which can be made longer or shorter at will in order to suit varying characters of terrain.

In the drawings:

Figure 1 is a view partly in section and partly broken away of one of my improved cement poles as erected;

Fig. 2 is a longitudinal elevation partly

in section of my improved pole, showing how the pole steps may be applied to same if desired;

Fig. 3 is a longitudinal, sectional elevation of part of the top of my improved pole showing the manner of attachment of the cross-arms thereto;

Fig. 4 is a partial view of the interior of the reinforcing metallic tube. This view also shows how the sockets for supporting the pole steps are detachably secured to said reinforcing tube;

Fig. 5 is a top plan view of the upper joint of the lower section shown in Fig. 2;

Fig. 6 is a bottom plan view of the lower joint of the lower section shown in Fig. 2.

My improved pole consists of a plurality of body sections such as 10, 10, etc.

All of the body sections of my improved pole are made in the same way. The top and bottom sections are made slightly different from the body sections as will be herein-after described.

Each of the body sections 10 consists of 80 a metallic reinforcement 11 provided with holes 12, or roughened or corrugated in any approved manner.

Circular flanges 13 and 14 are riveted respectively to the inside and the outside of the reinforcing tube 11 by rivets such as 15. Just above the upper edge of the reinforcing tube 11 the flanges 13 and 14 are respectively offset inwardly and outwardly to provide a recess 16 for a purpose hereinafter referred to.

A plurality of rivets such as 17 are riveted or otherwise secured in the flanges 13 and 14, the bodies of said rivets extending across the recess 16; the upper edges of the flanges 13 and 14 are beveled as at 18. The lower end of each reinforcing tube 11 is provided with a plurality of slots such as 19, equal in number to the number of rivets 17, which extend upwardly from the lower edge thereof as at 20, then turn approximately 90 degrees and extend a short distance circumferentially in a counter clock-wise direction, when looking upwardly at the bottom of the pole shown in Fig. 2, as at 21.

The reinforcing tube 11 is also provided with any desired number of holes as 22 arranged in pairs as shown in Fig. 4, each of said holes 22 being provided with a downward extension 23.

Sockets such as 24 are provided having a base 25 provided with two headed pins 26

on the inside of the base 25. These pins are the same distance apart as the holes 22; the heads of the said pins are slightly smaller than the upper portions of said holes and the bodies of said pins are slightly smaller than the outward extension 23 of the holes 22.

The socket 24 is otherwise shaped in any approved manner and all parts of same are cast integrally. The socket 24 is provided with an interiorly threaded hole for the reception of the pole step 27.

After the reinforcing tube 11 is constructed as just described, the sockets 24 are attached thereto if the pole steps such as 27 are to be used, and then the reinforcing tube 11 is introduced within a suitable mold and the cement covering 28 is applied to the inside and the outside of the said tube 11. The upper edge of the cement covering 28 is beveled as at 29 in line with the bevel edges 18 of the circular flanges 13 and 14. The lower end of the cement covering 28 is beveled at a salient angle as at 30 to fit the reentrant angle similar to 29 of the next lower section.

The upper end of the base 31 is formed the same as the upper end of the body sections 10 but the lower end of said base is flared outwardly as at 32 and the lower end thereof is formed to a plane surface, so as to provide a good bearing surface at the ground 33.

A grout mixture such as 34 may be used to fill the interior of the base 31 if desired.

The top 35 of my improved pole is provided with any number of gains such as 36 for the reception of the cross-arms 37. Said cross-arms are provided with a hole, or a plurality of holes, for the reception of a bolt or bolts such as 38.

The reinforcing tube 39 of the top of my improved pole is provided with straps of iron such as 40 riveted thereto, the said straps being provided with threaded holes for the reception of the bolts 38. The upper end of my improved pole is covered with cement as at 41 and the interior of the reinforcing tube 35 is preferably filled with cement as at 42.

The bottom, body and top sections of my improved pole are pre-cast and pre-aged so that the cement will be hard before the sections are shipped from the factory. The bottom section 31 may be omitted entirely or it may be made to conform to the shape of the rest of the pole omitting the flare portion 32.

When the sections are to be assembled in the field, the bottom section 31 or the section similar to 10, if the bottom section is not to be used, is placed in the foundation hole provided in the ground 33, grouting such as 43 of a suitable consistency is then poured into the recess 16 to fill up nearly to

the top of the bevel portion 29 of the body section 10. The next upper section is then to have the lower protruding portion of the reinforcing tube 11 introduced within the recess 16 so that the body of the rivets 17 will enter part 20 of the slot 19, the upper section is then turned in a counter clockwise direction, thus causing the portions 21 of the slots 20 to embrace the body portions of the rivets 17, thus locking the upper and lower sections together with the grout mixture filling the interstices between the said sections and the recess 16. The two sections are then firmly locked together by a bayonet joint, the grout mixture securing the permanence of the joint and the protection of the metal from the weather.

All the sections of the pole are secured together in this manner which insures that the pole, when completed, shall be extremely strong and able to resist the wearing action of the elements.

The pole when thus assembled is substantially parabolic or tapering in longitudinal, central section, and circular in cross section.

I claim:

1. The combination with a cement covering of a reinforcing tube extending at one end beyond said cement covering, and provided with L-shaped slots, a recess at the other end of said tube, and fixed rivets having bodies extending into said recess and grouting in said recess.

2. The combination with a cement covering, of a reinforcing member extending below said cement covering and provided with L-shaped slots, a second cement covering having a reinforcing member provided with a recess at its upper end, fixed rivets having bodies extending into said recess and adapted to form a locked joint with the slots of said first named reinforcing member by a partial rotation of said first named member and grouting in said recess.

3. The combination with a cement covering, of a reinforcing tube extending below said cement covering and provided with L-shaped slots, a second cement covering having a reinforcing tube provided with a recess at its upper end, fixed rivets having bodies extending into said recess and adapted to form a locked joint with the slots of said first named reinforcing member by a partial rotation of said first named member and grouting in said recess and between said cement coverings and grouting in said recess.

4. The combination with a reinforcing tube of a cement covering on the inside and outside of said tube and having a lower salient V-shaped end, the lower end of said reinforcing tube being provided with locking means and extending below the point of said salient V-shaped end; a second reinforcing tube having co-operating locking

means at its upper end to receive the locking means on the lower end of said first named reinforcing tube and provided with a cement covering on the inside and outside of said tube having a reentrant V shaped groove to fit the salient V shaped lower end of the cement covering of said first named reinforcing tube, and grouting in said recess and between said V shaped end and groove.

5. The combination of a reinforcing tube 10 provided with a slot, a cement covering and a pole step socket extending to the outside of said covering and having a member adapted to lock with said slot and a flat surface to bear against said tube. 15

In testimony whereof I affix my signature.

GEO. T. SOUTHGATE.
